UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

OIL-STOVE.

1,323,215.

Specification of Letters Patent. Patented Nov. 25, 1919.

Application filed April 2, 1917. Serial No. 159,136.

To all whom it may concern:

Be it known that I, LEE S. CHADWICK, a citizen of the United States, residing at East Cleveland, in the county of Cuyahoga and State of Ohio, have invented a certain new and useful Improvement in Oil-Stoves, of which the following is a full, clear, and exact description, reference being had to the accompanying drawings.

10 This invention pertains to an improved wick carrier for use with oil stoves or burners of the type wherein a tubular wick is supported by and about a wick tube, the wick being equipped with a carrier for co-15 operation with the wick raiser.

It is essential that an accurate and definite adjustment be maintained between the carrier and wick so that, as the wick is raised, it will be affected alike at all points 20 throughout its circumference and will produce an even flame of substantially the same length and character all the way around. Wicks of the sort in question, as is well known to those familiar with the 25 subject, are loosely woven and very soft (so as to readily absorb the oil and by capillary attraction conduct it to the upper end or exposed portion of the wick), and because of these characteristics the wicks 30 are easily stretched out of shape and normal size. In fact, the wicks are so elastic that to an experienced person they would seem to be over-size as compared to the carriers and wick tubes wherewith they are in-35 tended for use, and would require considerable manipulation to fit them to these parts.

Heretofore wicks have been furnished to the public by stove manufacturers of a size 40 and shape suitable for use with the type of stove above referred to, and the user has had to remove the wick carrier from the stove, discard what remains of the old wick, fit the new wick within the carrier, and then 45 introduce the wick and carrier into the stove or burner.

This operation has been found tedious and extremely difficult in the unskilled and inexperienced hands of the users, and invariably some detail essential to properly placing the wick within the carrier has been neglected or overlooked which results in the failure of the stove to properly perform its function and consequently in a general condemnation of the stove.

It is the objects of this invention to provide, for presentation to the trade as a single unit, a wick and an inexpensive wick carrier permanently united in proper relation to each other; which is of such nature 60 as to reduce to a minimum the work of inserting a new wick into a stove or burner, enabling persons unskilled and unacquainted with the principles of the stove or burner to properly insert a new wick without the 65 difficulties above set forth; which insures subsequent satisfactory operation of the stove, so far as the wick is concerned; and which may involve means for temporarily holding the wick distended and which fa- 70 cilitates the application of the wick to the wick tube of the burner, such means remaining within the wick during storage and shipment, and preferably being automatically displaced by a part of the burner dur- 75 ing the application of the wick.

A further object is to locate the means for connecting the wick and carrier below the plane of the carrier stops so that interference of such means with the operation of 80 the wick carrier is impossible.

In the accompanying drawings, Figure 1 is a perspective view of the unit comprising a wick and wick carrier; Fig. 2 is a central vertical section through the same; and Fig. 85 3 is a central vertical section through a stove, showing a wick and wick carrier unit therein.

The wick, which is designated 1, is of tubular form, slit upward from its lower end 90 on each side, as indicated at 2, and spaced downward a suitable distance from the upper end of the wick and completely surrounding it, is the carrier 5. The carrier is of thin cheap metal, and is freely per- 95 forated, as indicated at 6. The upper and lower edges of the carrier are provided with teeth 8 which are embedded into the material of the wick so as to hold the wick to the carrier throughout its circumference. 100 Stops 9 are struck out from opposite sides of the carrier, for a purpose which will be presently explained, and below the horizontal plane of these stops, the wick is permanently secured to the carrier by rivets 10. 105 When the wick and carrier are not in use—that is, during storage and shipment—a tube 12, preferably of paste board or other inexpensive material, occupies the upper portion of the wick and extends downward from the 110

top of the wick to a point well below the upper end of the carrier, the tube 12 being of substantially the same diameter as the inner wick tube of a stove or burner.

5 In Fig. 3 I have shown a type of stove wherewith my invention is adapted for use. The stove comprises a reservoir 15, centrally within which is supported a wick tube 16, and a flame spreader 17 repose within the 10 upper end of this tube. What is known as a gallery 20 has a threaded portion that is adapted to be screwed into a threaded opening in the top of the reservoir, and the bottom of the gallery is turned inward where 15 it has connected to it the lower end of an outer wick tube 21.

When it is desired to rewick a stove, the flame spreader is disconnected from an anchorage ring 25, fixed within the inner wick 20 tube, and is removed. The gallery is unscrewed and lifted upwardly from about the inner wick tube. After the old wick has been withdrawn from the inner wick tube, the split lower end of new wick is projected 25 down over the wick tube 16 with one of the slits 2 astride the wick raiser pinion 26, secured to the spindle 27. Thus the wick may be lowered until the pinion 26 is only a slight distance below the wick carrier before it is 30 obstructed by the pinion. Now by forcing the wick carrier farther downward, the pinion 26 is caused to ride over the brief extent of wick between it and the carrier until it is engaged by the lower end of the carrier and 35 rotated to project its teeth into the perforations 6. Now upon rotating the spindle 27 in the proper direction by the usual operating handle connected thereto exterior of the reservoir 15, the wick carrier and wick may 40 be fed downward along the tube 16, the temporary tube 17 meanwhile being forced out of the upper end of the wick by its engagement with the upper end of the inner wick tube.

45 By reason of the permanent connection between the wick and carrier; the holding of the wick firmly to the upper end of the carrier throughout its circumference by the teeth 8 (wherewith the wick is maintained 50 in engagement by the tube 12 until the wick is finally in place, and thereafter by the tube

16); and by reason of the further fact that the upper end of the wick is previously treated by the manufacturer so that it is in condition for immediate use and bears a 55 proper relation to the wick carrier, the stove is ready for service as soon as the wick has been inserted and the gallery 20 and flame spreader 17 have been returned to their respective places.

60 Excessive upward movement of the wick carrier is prevented by the engagement of the stops 9 with the bottom of the outer wick tube 21, and since the rivets 10 are below the plane of the stops no interference 65 between the rivets and adjacent parts of the structure is possible.

The pliability of the wick material allows the inner ends of the rivets 10 to be so embedded into the material that there is no 70 chance of the rivets interfering with the operation of the wick upon the inner wick tube.

Having thus described my invention, what I claim is:—

75 1. In combination, a tubular wick, a wick carrier surrounding the wick, stops projecting from the outer side of said carrier, each stop having a portion arranged for engagement with an abutment, and fastening means 80 for attaching the wick to the carrier and situated on the side of the stops remote from their abutment engaging portions.

2. In combination, a wick, a wick carrier provided with projecting stops, and fastening means connecting the wick and carrier and protruding in the direction of the stops beyond the surface of the carrier and located below the plane of said stops.

3. In combination, a tubular wick, a carrier surrounding the wick, said carrier being provided with laterally extending stops, and rivets connecting the wick and carrier the heads whereof project beyond the outer surface of the carrier and are located below 95 the plane of the aforesaid stops.

In testimony whereof, I hereunto affix my signature in the presence of two witnesses.

LEE S. CHADWICK.
